UNITED STATES PATENT OFFICE.

HARRY H. BASSETT, OF FLINT, MICHIGAN.

DESIGN FOR AN INSTRUMENT-CASE BEZEL.

Application filed November 19, 1923. Serial No. 7,821. Term of patent 14 years.

To all whom it may concern:

Be it known that I, HARRY H. BASSETT, a citizen of the United States, and a resident of Flint, county of Genesee, and State of Michigan, have invented a new, original, and ornamental Design for Instrument-Case Bezels, of which the following is a specification, reference being made to the accompanying drawing, forming a part thereof.

In the drawing, the figure is a front elevation of an instrument case bezel, showing my new design.

I claim:

The ornamental design for an instrument case bezel, as shown.

HARRY H. BASSETT.
